(57) **CLAIM**

The ornamental design for a lighting apparatus, as shown and described herein.

DESCRIPTION

FIG. 1 is a perspective view of a lighting apparatus showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a perspective view of a bottom portion thereof;

FIG. 9 is an enlarged view of a front portion of the lighting apparatus shown in FIG. 1;

FIG. 10 is an enlarged view of a rear portion of the lighting apparatus shown in FIG. 1;

FIG. 11 is an enlarged view of a front portion of the lighting apparatus shown in FIG. 2;

FIG. 12 is an enlarged view of FIG. 4;

FIG. 13 is an enlarged view of a front portion of the lighting apparatus shown in FIG. 6; and,

FIG. 14 is an enlarged view of a front portion of the lighting apparatus shown in FIG. 8.

The broken lines illustrate portions of the lighting apparatus that form no part of the claimed design.
